The ornamental design for a disposable cell phone holder, as shown and described.

DESCRIPTION

FIG. 1 is a perspective view of a disposable cell phone holder; FIG. 2 is a front view of the disposable cell phone holder of FIG. 1; FIG. 3 is a back view of the disposable cell phone holder of FIG. 1; FIG. 4 is a top view of the disposable cell phone holder of FIG. 1; FIG. 5 is a bottom view of the disposable cell phone holder of FIG. 1; FIG. 6 is a right side view of the disposable cell phone holder of FIG. 1; FIG. 7 is a left side view of the disposable cell phone holder of FIG. 1; and, FIG. 8 is a front view of the disposable cell phone holder of FIG. 1 in an unfolded, alternate configuration of use. The unfolded disposable cell phone holder of FIG. 8 is flat and of minimal thickness. The back view of the unfolded disposable cell phone holder of FIG. 8 is identical to the front view of the unfolded disposable cell phone holder of FIG. 8. The broken lines in FIG. 8 are included for purposes of illustrating portions of the disposable cell phone holder, namely folding lines, and form no part of the claimed design.
